UNITED STATES PATENT OFFICE.

HERBERT E. SPEYER, OF KNOXVILLE, TENNESSEE, ASSIGNOR TO ECONOMY RAIL COMPANY, A CORPORATION OF TENNESSEE.

RAILWAY-TRACK.

1,314,024.

Specification of Letters Patent. Patented Aug. 26, 1919.

Application filed October 6, 1917, Serial No. 195,179. Renewed January 18, 1919. Serial No. 271,885.

To all whom it may concern:

Be it known that I, HERBERT E. SPEYER, a citizen of the United States, residing at Knoxville, in the county of Knox and State 5 of Tennessee, have invented a new and useful Improvement in Railway-Tracks, of which the following is a specification, reference being had to the accompanying drawing.

My improvement relates particularly to 10 railway tracks used for the running of relatively light cars, such cars as are used in mines and quarries and similar situations.

The object of the invention is to provide 15 a track construction requiring the use of a minimum amount of steel or iron in forming the rails and in which the term of service can be prolonged by change of position of parts, and in which the members forming the rails are interchangeable and reversible, 20 and in which provision is made for the easy and effective joining of the meeting ends of the rails.

In the accompanying drawings,

Figure 1 is a plan of a piece of trackage 25 embodying my improvement;

Fig. 2 is an upright cross section on the line, 2—2, of Fig. 1, looking toward the right;

Fig. 3 is a perspective view of a rail, portions being broken away;

Fig. 4 is a perspective view showing the ends of two rails in alignment with each other in position to be moved endwise toward each other into the working position;

Fig. 5 is a plan of an angle bar cut into form for bending to become a part of a frog;

Fig. 6 is a wood block which is to be cut for forming the body of a frog;

Fig. 7 shows the body of a frog;

Fig. 8 shows a complete frog.

Referring to said drawings, A, A, are ordinary wood ties of any desired dimensions, for example, four inches high and five inches wide. B, B, are main track rails 45 resting on said ties. C, C, are branch track rails resting on said ties.

The rails of said tracks are composed of a wood member, D, and a metal member, E. The wood member, D, is of suitable 50 shape to adapt it to be seated firmly upon

the ties and to form a firm seat for the metal member. In practice I have made the wood member two inches high and four inches wide and ten feet long, one of the wide faces resting flatwise on the ties. (See particularly Fig. 2). The members, D, of adjacent rails are made to abut endwise against each other.

The metal member, E, is of angle form in cross section and is laid parallel to and upon 60 the wood member, D, on the inner upper edge thereof. In practice I have used angle steel having flanges one and one-half inches wide and three-sixteenths of an inch thick, the length of said member being ten feet, 65 the same as the length of the wood member. But, in placing the metal angle member on the wood member, the ends of the angle member are not made even with the ends of the wood member. On the contrary, the 70 angle member is placed upon the wood member so as to leave twelve inches, or some other desired length, project at one end, while at the other end the wood member projects an equal distance. The angle member 75 is secured to the wood member by nails, F, extending through holes, G, formed in the flanges of the angle member, the nails extending through the upper flange being upright and the nails extending through the 80 upright flange being horizontal. The number of nails thus used is to be sufficient to firmly secure the metal member to the companion wood member. In the flanges of the projecting portion of the angle member are 85 formed holes, H, H. When the rails are placed into working position on the ties, such projecting portion of the angle member extends over the adjacent wood member, D. Since the projecting portions of the 90 angle members and of the wood members are made equal, the projecting portion of the angle member will extend along the projecting end of the wood member of the adjacent rail and meet the end of the flange 95 member which forms a part of the companion rail. When two adjacent rails are thus placed end-to-end in the working position, nails, F, are driven through the holes, H, H, into the wood member on which said 100

projecting portion of the flange member now rests. By this means continuity of the metal surfaces is established and the two rails are joined to each other; the angle member serving the double purpose of a metallic tread and as a substitute for a fish plate. The holes, H and G, are to be counter-sunk, in order that the heads of the nails may not project outside of the faces of the angle member.

The wood members are secured to the tires by upright nails or spikes, I, extending through said members into the ties.

In manufacturing, the wood members, D, are all cut of the same thickness, width, and length, and they need no special shaping, and they can be placed with either end in either direction and with either of the two broad faces turned upward. The angle members are of ordinary iron or steel angle shape readily procured on the market and needing no special shaping. They require merely to be cut crosswise and to be provided with the holes, G and H. As above stated, the length of these angle members is the same as the length of the wood members. Hence, if the wood members are cut to a length of ten feet, the angle members are also cut to a length of ten feet. Forms or gages may be used for applying the angle members to the wood members with uniform projection of the ends. In applying the angle member to the wood member, either end of the angle member may be applied to a chosen end of the wood member, this involving placing either of the flanges of the angle member upon the upper face of the wood member. When thus completed, the rails (consisting of a wood member and an angle member) are to be transported to the place where the tracks are to be laid, and they are in convenient form for such transportation.

When the tracks are in use, the upper flange of the angle member forms a tread for the car wheels, while the upright flange of the angle member resists bending of the horizontal flange and also takes wear from the flanges of the car wheels. When the angle member has been used long enough to wear away and thus weaken the horizontal flange, the angle member may be detached from the wood member and turned end-for-end and again secured to the wood member, thus bringing the other of the flanges of the angle member upon the upper face of the wood member and making said flange serve as a tread for the car wheels.

The manner of joining two tracks by means of a switch will next be described.

At B¹ one of the rails B, B, is curved out of the course of the main track into the course of one of the rails of the switch track and joined to said rail at B². A frog, J,

(Figs. 1 and 8) is set into the course of the other rail, C, and of the adjacent rail, B, of the main track. A rail section, K, is placed into the course of said rail, B, in the space between the apex of said frog and the rail portion, B¹, a gap, K¹, being left at each end of the section, K, for the passage of flanges of the car wheels. From the apex of the frog, J, a switch point, L, extends diagonally across the space between the rails, B, B, in the course of the adjacent rail of the switch track. Adjacent said frog an upright bolt, L¹, extends through the switch point, L, into the adjacent tie, whereby said point is pivoted for movement in the horizontal plane. Between the point of the frog and the switch point, L, is a space, L², wide enough for the passage of the flanges of the car wheels. When the free end of the switch point, L, is set away from the adjacent rail, B, cars approaching the switch from the right will continue on the main track. When the free end of said switch point is in the contact with the adjacent rail, B, the wheels of a car approaching from the right will be turned by said point onto the switch track, the flanges of the car wheels going through the gaps or spaces, K¹, K¹.

The rail section, K, is composed of a wood member, D, and a metal angle member, E, as already described concerning the full length rails; but the ends of the section, K, are cut obliquely so as to form upright faces parallel to the course of the rails, C, C. The switch point, L, is also formed of a wood member, D, and a metal angle member, E, similar to the construction of the full length rails; but the wood member of said point is curved to make a gradual approach toward the outer rail, B; and the free end of the point, L, is cut diagonally in an upright plane to form an upright face, L⁴, to lie against the adjacent rail, B, and establish approximate continuity between the inner upright faces of said rail and said point.

The frog, J, is composed of a wood body, J¹, and an angle member, E. The wood body, J, is in the form of an elongated triangle. Said body may be economically made by cutting a rectangular block of wood (Fig. 6) along the diagonal line, J³, to form two pieces, J², and then reversing one of said pieces and joining the pieces edge-to-edge as shown in Fig. 7. Near the middle of an angle member, E, of proper length, the horizontal flange is cut away, as shown in Fig. 5, on angles which will allow the cut edges, J⁴, of said flange to meet when the member has been bent horizontally, on the apex of the angle formed by said cut faces, far enough to allow the angle member to be fitted to the side edges of the body, J¹, of the block. At one side of the block, the

angle member projects beyond the wood member, J^1 , a distance equal to the projection of the angle members on the rails, and at the other side of the frog, the angle member is correspondingly shorter than the adjacent side of the wood member, whereby the latter projects said distance beyond the angle member. Thus any one of the complete rails may be applied to either side 10 of the frog, the angle member of said rail in one case overlapping the wood member, J^1 , of the frog and the angle member of the frog, in the other case overlapping the wood member of said rail.

15 The frog is secured to the ties by means of large nails or spikes.

I claim as my invention,

1. In the art herein described, a rail comprising a wood member and a reversible metal angle member, said members being of equal length and the wood member having upright and horizontal longitudinal faces and the angle member having flanges either of which is suited to be placed on the upper 25 face of said rail for use as a tread for wheels, and the angle member being applied lengthwise of the wood member with one flange resting on the upper horizontal face of the wood member and with the other flange resting 30 against one of the side upright faces of the wood member, and means extending through said flanges and into the wood member for securing the angle member and the wood member to each other, substantially as described.

2. In the art herein described, a rail comprising a wood member and a reversible metal angle member, said members being of equal length and the wood member having 40 upright and horizontal longitudinal faces and the angle member having flanges either of which is suited to use as a tread for wheels, and the angle member being applied lengthwise of the wood member with 45 one end projecting beyond the adjacent end of the wood member and with one flange resting on the upper horizontal face of the wood member and with the other flange resting against one of the side upright faces 50 of the wood member, and means extending through said flanges and into the wood member for securing the angle member and the wood member to each other, substantially as described.

55 3. A railway track formed of ties and rails comprising a wood member and a reversible metal angle member, said members being of equal length and the wood member having upright and horizontal longitudinal faces and the angle member having 60 flanges either of which is suited to be placed on the upper face of said rail for use as a tread for wheels, and the angle member being applied lengthwise of the wood mem-

ber with one flange resting on the upper 65 horizontal face of the wood member and with the other flange resting against one of the side upright faces of the wood member, and means extending through said flanges and into the wood member for securing the 70 angle member and the wood member to each other, substantially as described.

4. A railway track formed of rails comprising a wood member and a reversible metal angle member, said members being 75 of equal length and the wood member having upright and horizontal longitudinal faces and the angle member having flanges either of which is suited to use as a tread for 80 wheels, and the angle member being applied lengthwise of the wood member with one end projecting beyond the adjacent end of the wood member and with one flange resting on the upper horizontal face of the wood member and with the other flange 85 resting against one of the side upright faces of the wood member, and means extending through said flanges and into the wood member for securing the angle member and the wood member to each other, the projecting portion of the angle member overlapping and being secured to the wood member of the adjoining rail, substantially as described.

5. A main railway track and a switch 95 track formed of rails comprising a wood member and a reversible metal angle member, said members being of equal length and the wood member having upright and horizontal longitudinal faces and the angle 100 member having flanges either of which is suited to use as a tread for wheels, and the angle member being applied lengthwise of the wood member with one flange resting on the upper horizontal face of the wood member and with the other flange resting against 105 one of the side upright faces of the wood member, and means extending through said flanges and into the wood member for securing the angle member and the wood member to each other, and a frog composed of a wood body and a single angle member extending along two sides of said body and having one flange cut away at 110 the point of the frog, substantially as described.

6. A main railway track and a switch track formed of rails comprising a wood member and a reversible metal angle member, said members being of equal length and the wood member having upright and horizontal longitudinal faces and the angle member having flanges either of which is suited to use as a tread for wheels, and the angle member being applied lengthwise of 120 the wood member with one flange resting on the upper horizontal face of the wood member and with the other flange resting 125

against one of the side faces of the wood member, and means extending through said flanges and into the wood member for securing the angle member and the wood member to each other, and a frog composed of a wood body and an angle member, the wood body projecting at one side and the

angle member projecting at the other side of the frog, substantially as described.

In testimony whereof I have signed my name, this 25th day of September, in the year one thousand nine hundred and seventeen.

HERBERT E. SPEYER.
